Primary Examiner—Carol Rademaker(74) Attorney, Agent, or Firm—Cynthia R. Miller(57) CLAIM

The ornamental design for a fragrance bottle and cap, substantially as shown and described.

DESCRIPTION

FIG. 1 is a top, front and right side perspective view of a new design for a fragrance bottle and cap;

FIG. 2 is a front elevation view of the fragrance bottle and cap shown in FIG. 1;

FIG. 3 is a rear elevation view of the fragrance bottle and cap shown in FIG. 1;

FIG. 4 is a right side elevation view of the fragrance bottle and cap shown in FIG. 1, a left side elevation view being a mirror image thereof;

FIG. 5 is a top plan view of the fragrance bottle and cap shown in FIG. 1; and,

FIG. 6 is a bottom plan view of the fragrance bottle and cap shown in FIG. 1.

The broken lines shown in the figures are for illustrative purposes only and form no part of the claimed design.
